GENERAL CONTAINER AND CLOSURE AND
TOOTHED ARTICLE THEREFOR

Martin Simsiovici, Paris, France

Application April 6, 1933, Serial No. 664,820
In Canada December 27, 1932

4 Claims. (Cl. 229—5.5)

This invention relates to improvements in cover plates for boxes, cases, cartons or similar containers capable of general use as, for instance, in the packaging of bonbons, bottles, dry batteries, accumulators and the like as well as to the application directly of the container to the article enclosed therein.

The principal object of the invention is to provide for the convenient and economical packaging or enclosing of articles and consists in the provision of a toothed or undulated surface on that portion of the closure which is presented to the wall of the container and in the application of pressure to the container, after the introduction of the closure therein, whereby the material of the container is upset and entering into the cavities or interstices of the toothed area forms a rigid and secure connection between these parts.

20 The material of the closure member is suitably chosen in dependence on the particular use to which the container is to be applied. It is essential, however, that the material of the closure have sufficient strength and rigidity to 25 withstand the application of pressure such as required to compress the wall of the container into the interstices of the toothed area.

In the accompanying drawing wherein an approved embodiment of the invention is illustrated:

Fig. 1 is a fragmentary sectional view of a flashlight embodying the present improvement.

Fig. 2 is a modification of the closure member.

Fig. 3 is a perspective view, partly in section, 35 of a further modification of the closure member.

Figs. 4 and 5 are perspective views illustrating the invention applied to a carton suitable for containing, for example, a bottle of perfume or the like.

40 Fig. 6 is a sectional view through a further modification of the invention as applied to a container for bottles.

Fig. 7 is a perspective view of a form of closure 45 suitable for application to containers and which is provided with an opening or window.

Fig. 8 is an elevation of a further modification of the invention, partly broken away and in section.

50 Fig. 9 is an enlarged detail through the closure member and a portion of the wall of the container.

Figs. 10-12 are detail views in section of further modifications of the invention.

55 Referring to the drawing in detail and more

particularly to Fig. 1, the invention is shown as applied to a battery carton.

According to this embodiment of the invention, the carton is constructed to adapt it for use as a flashlight by the mere introduction of an electric lamp and does not require the usual metallic case. The invention presents the further advantage in that the usual filling material of tar or like substances for retaining the cells of the battery in position is dispensed with. The battery carton 10 formed of pasteboard or like material encloses one or a series of electric cells 11. At the end of the carton or container 10 where the electrodes of the cells 11 are located, a closure member 12 preferably formed of insulating material and having a relatively high degree of resistance to pressure, is inserted. The closure member 12 is shaped in conformity with that of the container 10 and, as will be understood, may be oval, circular or rectangular.

The closure member, however, is of substantial thickness, that is to say, it is considerably thicker than the material forming the container 10 and is provided on its relatively wide lateral edge with a plurality of laterally projecting teeth 13 or undulations. The closure member 12 is primarily formed of such size so as to initially fit in comparatively snug relation in the terminal of the container 10, and after insertion therein pressure is exerted on the portion of the container 10 overlying the wide toothed edge 13 of the member 12 and sufficient pressure is exerted thereon to upset the material of the wall of the container 10 and cause the latter to be upset and to enter into the spaces between the teeth of the member 12.

When the pressure is relieved, the container wall 10, being formed of pasteboard or like plastic material, remains in intimate contact with the irregular edge surface of the member 12, and thus these two parts are rigidly and securely united.

According to Fig. 1 the closure member 12 is provided with a central opening 14 which is of frusto-conical form and of such size at its relatively small outer end as to fit into the threads of the base of an incandescent lamp 15 which latter may be thus threaded into the aperture 14 and by rotary movement is advanced therein until it reaches proper position.

At one side, the closure member 12 is provided with an upstanding partial flange 16 of greater height than the bulb of the lamp 15 and in case the flashlight is dropped or supported in an inverted position, the lamp 15 is protected from in-

jury. One of the usual spring electrodes 17 of the electric cell 11 is disposed, as usual, to engage the center electrode of the lamp 15, when the latter is properly positioned while the other electrode 18 is engaged by a switch member 19 loosely fitted in an outwardly tapering aperture 20 provided in the closure 12. The inner extremity 21 of the switch 19 is movable into engagement with the lateral electrode or metallic shell of the lamp 15 and, being engaged with the electrode 18, completes the circuit to the lamp 15 causing the latter to light. The loose mounting of the switch member 19 permits the latter to be either turned or pushed laterally into a position to engage the lamp base and thereby complete the circuit of the latter.

Fig. 2 illustrates a modification of the invention in which the closure member 12a is provided with a toothed lateral edge 13a formed with a flange-like projecting part 22. The toothed edge of the closure member fits within the container 10a and the latter is fitted with the lateral stud 23 having a head 24 at the outer end. The body or shank portion 23 of the stud is initially of such length as to enter into the recess 25 provided in the toothed edge portion of the closure member 12a and the edges of the recess 25 are undercut as indicated at 26. Incident to the application of pressure to the wall of the container 10 for the purpose of uniting the container 10a with the toothed edge of the closure member 12, the shank portion 23 of the stud is upset in the recess 25 and a head as indicated at 27 is thus formed which, engaging beneath the undercut edges 26 of the recess firmly anchor the closure member 12a in position in the container 10a.

Fig. 3 illustrates a modification of the closure member in which the edges thereof are formed with flanges 30 providing a lateral edge having the teeth 31 thereon which are adapted to coact with the walls of the container in connection with which the closure member is used. Aside from increasing the area of the side edges of the closure member, the flanges 30 also increase the strength thereof. The closure member is provided with tapered or conical holes 32 for receiving the sockets corresponding to the cells and the surface thereof may bear corresponding indications of voltage, advertisement, text and the like. A strip of material 33, such as paper, may be applied over the holes in the closure member so as to close said holes until such time when the battery is put in use. The strip 10 may have its extremities continued beyond the edges of the cover and secured in any suitable manner to its under side.

The conical holes 32 serve to center and retain electrodes of the cells of the battery (not shown) in position thereby dispensing with the use of tar and like filling substances which are ordinarily poured over the tops of the cells to close the battery box and form a unit.

To facilitate the introduction of the closure member into the open end of the container, the surfaces of the relatively wide edges of the plate are sloped or inclined in such manner that said closure member is smaller at one side than the other and may thus be freely inserted in the container. The difference in the sizes of the front or entering portion of the closure member and the rear thereof is clearly shown in the construction shown in Figure 2 and this principle, as will be understood, may be applied to all the forms of the invention.

Figs. 4 and 5 illustrate a further modification of the invention in which the container or carton

34 is of substantially box-like form and is open, for instance, on two sides, as indicated at 35 and 36. The closure member 37 is of angular form and so shaped as to fit into the open sides of the container 34, the edges 38 of the closure member having undulations or teeth thereon which, when the closure member is inserted between the walls of the container 34, are adapted to cooperate with the material of said container whereby upon the application of pressure such material is caused to fill the space between the teeth and thereby firmly secure the closure member in position. By thus securing the closure member in place the contents of the container are enclosed and sealed.

After removing the closure member, it may be arranged in the position shown in Fig. 5 in which it will stand upright forming a support or stand for an advertisement, a calendar or the like.

As suggested in the modification illustrated in Fig. 7, the closure member 40 may be perforated at its center as indicated at 41 and the perforation in any shape desired may be filled with a panel of suitable material or the opening may be left free thereby providing a window. The edge of the closure member illustrated in Fig. 7 is provided with teeth of different shapes and, as indicated at the medial portion of the upright edge, the teeth may be arranged in parallel rows or, as indicated at the lower portion of said member, the teeth may extend entirely across the edge of the closure member. The teeth at the upper part of this figure are produced by oblique rows of projections.

Fig. 7 also illustrates the provision of a cord-like member 42 suitably attached to the closure member 40 as by passing the terminal of the cord through an aperture therein. The cord is preferably provided at its free end with a knob-like part 43 which may be conveniently grasped for the purpose of withdrawing the closure member from the container.

Fig. 6 illustrates a further modification in which the invention is applied to a container for bottles and like fragile articles. In this case the container 44 is of tubular form and is closed at one end by a closure member 45 the lateral teeth 46 of which are firmly connected with the interior of the container wall 44 by the application of pressure, as above described. The provision of the closure member 45 ensures the maintenance of shape of this end of the container 44 and, as will be understood, the latter may be suitably shaped in conformity with the shape of the article 47 to be enclosed therein.

It is desirable, however, that the opposite end of the container 44 snugly fit the bottom part 48 of the article, and for the purpose of increasing the security of mounting of the article the bottom portion thereof is provided externally with teeth. Thus, upon the application of pressure to the portion of the container 44 overlying the teeth on the bottom of the article 47, the latter is securely held in position.

In addition, the medial portion of the article 47 may be provided with teeth 49 which, by the application of pressure to the contiguous portion of the container, will further aid in maintaining the article in position.

According to this embodiment of the invention, the portion of the container 44 overlying the label 50 on the article 47 is preferably cut away to provide a window 51 through which such label is visible.

Fig. 8 shows a further modification in which

the article 52 is provided with a removable cap 53 threaded or otherwise secured on the open end of the article which latter, as indicated in this figure, is in the form of a jar. The cap 53 is provided with peripheral teeth 54 and the base or bottom portion 55 of the article 52 is somewhat enlarged and provided with additional teeth. In case the material of the container or article 52 does not possess sufficient rigidity 5 to withstand the pressure which is required to fasten the container in position, a band which may, for instance, be in the shape and dimensions corresponding to the part indicated at 55 in Fig. 8 is affixed to the article so as to increase 10 the strength of the latter at this point and permit the application of pressure to the wall of the container to unite the latter with the article. The jar together with the cap thereof is enclosed in a container 56 preferably provided with a window 57 and, as in the case of the above described 15 embodiments of the invention, these parts are initially closely fitted.

Following the insertion of the jar in the container, the walls of the latter are subjected to 20 the application of pressure and the material of the wall of the container is upset and enters between the spaces of the teeth thereby securely holding the jar at the bottom as well as at the top, through the medium of the cap 53. According to this embodiment of the invention, the 25 name of the article or maker or any other desired lettering may be embossed on the jar, as indicated at 58, and by the application of pressure to the extremity of the contiguous portion 30 of the container the latter is firmly united with the jar and the latter thereby more securely held in position.

Fig. 9 is an enlarged detail sectional view taken, for instance, through the contiguous portions 35 of the closure member and the container illustrated in Fig. 1. It will be noted that the material of the container 10 has been upset due to the application of pressure in the direction of the arrow indicated at 59 and enters into the 40 spaces between the teeth 13 of the closure member.

Fig. 10 illustrates a further modification of the invention applied to a flashlight of the torch type. In this case the casing or container 60 45 may be formed of any material such as paper, pasteboard, celluloid or metal, and a closure member 61 similar in construction to the closure member 12 in Fig. 1 is secured in position in the open end of the container. In this case the incandescent lamp 62 is threaded in an aperture 63 formed centrally of the closure member 61 and a switch member 64 is arranged in said closure member and adapted to be slid or turned into engagement with the lateral electrode of the 50 lamp 62. The outer electrode of the lower cell 65 is engaged with a spring contact 66 connected by an insulated conductor 67 with a spring contact 68 which engages with the switch member 64. The center electrode of the lamp 62 engages the center electrode of the adjacent electric cell 69, and upon proper manipulation of the 55 switch member 64 the circuit of said lamp is completed.

According to the arrangement shown in Fig. 11, the casing or container 60a is constructed of metal or like conducting material which is in electrical connection at its lower end with a center electrode of the lower electric cell. The 5 spring contact 68a is riveted and thereby electrically connected with the container 60a and engages the switch member 64. In other respects the construction of the torch light in Fig. 11 is substantially the same as that shown in Fig. 10. 10

In the arrangement shown in Fig. 12, the conductor connected with the center electrode of the lower electric cell resiliently presses the outer electrode of the lamp 62 while the center electrode of the latter may be connected with the center electrode 71 either by direct contact, as by screwing the lamp 62 into the closure member or by means of a movable switch member 72 mounted in a manner similar to the switch member 64 in Fig. 10, but provided at its inner end 20 with a spring contact 73 adapted upon proper manipulation to enter between the center electrode of the lamp and the center electrode of the adjacent electric cell. 25

What I claim is:

1. In combination, a container including a wall, a closure member fitted in said container and provided with relatively wide edges lying in facial contact with the inner surface of the container walls, undulations on substantially the entire edge surface of the closure member defining a plurality of depressions therein, the material of the container being pressed into the depressions of the cover member to secure the latter in position. 30

2. In combination, a container including a wall, a closure member fitted in said container and provided with relatively wide edges lying in facial contact with the inner surface of the container walls, undulations on substantially the entire edge surface of the closure member defining a plurality of depressions therein, the material of the container being pressed into the depressions of the cover member to secure the latter in position, said closure member being formed of rigid material, the individual undulations being of comparatively small width as compared with the width of said edges, and a plurality of said undulations being provided in the direction of said width of the closure member. 40

3. An arrangement as claimed in claim 2 characterized in that the material of the container is softer than the material of the closure member. 45

4. In combination, a container including a wall, a closure member fitted in said container and provided with relatively wide edges lying in facial contact with the inner surface of the container walls, said closure member being of smaller dimensions at one side than the other to facilitate its introduction into the container, undulations on the edge surface of the closure member defining a plurality of depressions therein, the material of the container being pressed into the depressions of the cover member to secure the latter in position. 55

MARTIN SIMSINOVICI.
